UNITED STATES PATENT OFFICE.

JOHN WALLACE TAYLOR, OF PHILADELPHIA, PENNSYLVANIA.

AUTOSELECTIVE FUSE.

1,313,930.

Specification of Letters Patent. Patented Aug. 26, 1919.

Application filed September 11, 1918. Serial No. 253,532.

To all whom it may concern:

Be it known that I, JOHN WALLACE TAYLOR, a citizen of the United States, and a resident of Philadelphia, in the county of 5 Philadelphia and State of Pennsylvania, have invented certain new and useful Improvements in Autoselective Fuses, of which the following is a specification.

My invention is an improvement in auto 10 selective fuses, and has for its object to provide mechanism in connection with the striker or plunger mechanisms of artillery fuses, for neutralizing the elastic energy of the recoil, to prevent the premature action 15 of the striker or plunger.

In the drawings:

Figure 1 is a vertical section through the fuse mechanism of a shell;

Fig. 2 is a partial side view of the locking sleeve.

As is known, artillery fuses frequently have plunger or striker mechanisms intended to function on impact with the target. It occasionally occurs, however, that the striker 25 is immediately driven forward by the recoil from the shock of impact, before the safety device can recover itself, thus firing the primer prematurely. In order to neutralize the elastic energy of the recoil and 30 so prevent the premature action of the striker, this invention introduces a shock pad to protect the features concerned.

The usual delayed action fuse has a definite predetermined delay period, and, therefore, does not give maximum results. The 35 object of the delayed action fuse is to prevent the action of the fuse until either the target is penetrated or the projectile comes to rest. This delayed action should vary 40 with the resistance and must automatically be taken care of by the mechanism of the fuse. For example, a shell striking the smoke stack or the rigging of a ship should explode without delay in order to damage 45 the vessel, but a shell striking the armor plate must delay sufficiently to penetrate the armor before exploding in order to attain a maximum amount of damage. It is desired to have such selective delay projectiles pierce a tank and explode inside, penetrate a wall and explode just in rear for destroying personnel, or enter the ground and explode when coming to rest for maximum mining penetration to destroy emplace- 50 ments.

However, delayed action fuses have been

erratic and unsatisfactory due to the fact that the initial shock of impact sets up a vibration in the mechanism with a sufficiently powerful impulse to cause the mechanism to function prematurely. 60

In order to dampen these disturbing vibrations, the present invention introduces a shock pad which absorbs the powerful recoil impulse and saves the starter from being 65 forced to act ahead of time, thus permitting the mechanism to function properly and to give the required delay.

In the ordinary type of auto selective delay, the mechanism is completely armed by 70 the force of impact with the target, but is prevented from functioning until the target is penetrated by the inertia forces of the component parts of the mechanism which are sufficient during penetration to overcome 75 the motive power of the mechanism. As the forward part of the projectile is being retarded by the target, any rearward and interior component parts of the mechanism exert a tremendous force ahead, due to their 80 inertia. Since this force is suddenly applied it causes an elastic deformation, considerably greater than that normally obtained with the same pressure. The metal, due to its elasticity, immediately attempts to return 85 to a state of equilibrium and in doing so naturally moves past the mark, setting up a vibration with rapidly decreasing amplitude. The elastic energy stored up in the initial deformation of the component parts 90 of the mechanism is almost entirely restored on the first surge of the vibration and, therefore, the inertia upon which the mechanism depends for its brake is momentarily neutralized and the device allowed to function. 95

The present invention, however, introduces a non-elastic element which is incapable of restoring energy and, therefore, cannot neutralize the inertia of the components, and so permits the mechanism to delay until 100 retardation of the projectile ceases. In the present embodiment of the invention the projectile, indicated at 1, carries at its nose or point the usual fuse stock 2 which has threaded engagement with the projectile and 105 extends into the shell charge (not shown), and the firing pin housing 3 has threaded engagement with the fuse stock at the open end thereof. The fuse stock carries a transverse partition 4 intermediate its ends and 110 within a central opening in the partition is threaded one end of the detonator casing 5.

This casing has the threaded end closed but provided with an axial opening, and the outer end of the said opening is recessed or counter-bored to receive the primer casing 5. The booster charge, indicated at 7, is arranged within the fuse stock between the partition 4 and the inner end of the stock. The cylindrical axial portion 8 of the firing pin housing has slidably mounted therein 10 a firing pin 9, the said pin being adapted at its pointed end to engage the primer to set off the charge, and the pin is normally pressed toward the primer by a coil spring 10 which encircles the pin between the closed 15 end of the extension 8 and an annular rib 11 on the pin.

The rib 11 has a radially extending latch pin 12 which engages a slot 13 extending longitudinally of the cylindrical extension 20 8. A key sleeve 16 is mounted in the extension 8, and this key sleeve has a longitudinally extending slot or notch 15 at its lower end for engagement by the pin.

At its upper end the sleeve also has a 25 notch or slot 17 which is engaged by a guide screw 18 on the extension 8. The slot 13 has at its upper end a lateral extension 13^a extended at an oblique angle with respect to the slot. A coil spring 19 encircles the cylindrical extension 8 between the sleeve 16 and the body of the firing pin housing, normally acting to move the sleeve toward the 30 primer.

The operation of the parts just described 35 is as follows: On the impact of the projectile with the target the locking sleeve 16 moves forward, compressing the light retaining spring 19, and releasing the pin 12, which has been held in the portion 13^a of the 40 slot 13 by the key sleeve 16. The inertia of the firing pin retains the actuating spring 10 thereof under compression, until retardation of the projectile ceases, when the spring immediately drives the pin into the primer 45 6, exploding the shell.

In order to absorb the impact forces of the striker and dampen any possible vibration that would cause the firing pin to act

prematurely a shock pad, indicated at 20, is arranged between the firing pin or striker 50 and the closed end of the bore of the cylindrical extension 8 of the firing pin housing. This shock pad is composed of any suitable non-elastic material, as, for instance, fiber, lead or annealed copper, and the said pad 55 absorbs the impact force of the striker and dampens any possible vibration. The very low coefficient of restitution of lead makes it especially adapted for use in this connection. 60

I claim:

1. In a shell, the combination with the primer, the spring operated striker and the impact released holding mechanism for the same, of a shock absorbing pad between the 65 striker and the impact end of the shell for absorbing the shock of impact and preventing premature movement of the striker toward the primer.

2. In a shell, the combination with the 70 primer, the spring operated striker and the impact released holding mechanism for the same, of a pad having a low coefficient of restitution between the striker and the impact end of the shell for the purpose specified. 75

3. In a shell, the combination with the auto selective fuse mechanism, of a shock pad for neutralizing the elastic energy of recoil to prevent premature action. 80

4. The combination of a shock pad with a fuse mechanism to neutralize the elastic energy of recoil and so prevent the premature action of the striker by accident during transportation. 85

5. The combination of a shock pad with an auto selective delay fuse to absorb the recoil impulse of target impact and prevent the neutralizing of the inertia forces of the mechanism components. 90

6. The combination of a shock pad with projected mechanisms to dampen the disturbing vibrations due to shock of target impact.

JOHN WALLACE TAYLOR.
